UNITED STATES PATENT OFFICE.

WARD LEATHERS, OF HAWORTH, NEW JERSEY, ASSIGNOR, BY MESNE ASSIGNMENTS,
TO RADIO CORPORATION OF AMERICA, A CORPORATION OF DELAWARE.

RADIO-PHONOGRAPH COMBINATION.

Application filed May 3, 1922. Serial No. 558,208.

My invention is for the purpose of applying a radio actuated vibrator directly to the diaphragm of a phonograph.

One of the objections to present day radio 5 loudspeakers is the unmusical sound produced by the magnetic diaphragm as is common to telephones. My invention makes it practicable to use the mica or other highly sensitive and musically-toned diaphragm of 10 the phonograph.

An object of my invention is to make the use of the same diaphragm possible for both radio and phonographic use.

Another object of my invention is to make 15 it possible to use, for radio receiving purposes, the entire phonograph reproducer and amplifying horn as now in common use.

Another object of my invention is to change 20 the same reproducer from phonographic to radio receiving use with the minimum of effort.

Another object of my invention is to use 25 the nicely adjusted counter-pressure springs of present day phonograph reproducers in the translation of radio received vibrations into sound.

Another object of my invention is to produce 30 a device whereby whatever spring adjustment may be required for correct radio sound production the same need not be changed in changing from radio to phonograph reproduction and vice versa.

I have fully set forth my invention in the 35 following specification and illustrated the same with drawings of which—

Fig. 1 is a vertical cross-section of my device when used with lateral-groove reproducer.

Fig. 2 is another view of the same.

Fig. 3 is a detail of the same.

Fig. 4 is a vertical cross-section of the same device showing a modification.

Fig. 5 is a vertical cross-section of my device when used with a hill-and-dale 45 reproducer.

Fig. 6 is a detail of the same.

Fig. 7 shows two right-angled lever-arms.

Fig. 8 is the same as Fig. 4 with a spring modification.

Fig. 9 is a horizontal cross-section of my device when directly applied to a phonograph reproducer.

Fig. 10 is a side elevation of a modification of my construction.

Fig. 11 is an end view of Fig. 10.

Fig. 12 is a partial sectional view of my modified construction.

Fig. 13 is a detail of holder devices.

In Fig. 1, 1 is the table, 2 the turn-table, and 3 the reproducer of a phonograph. 4 shows the usual opposed springs used on lateral-groove instruments, 5 is the stylus, and 6 is a frame or case for my instrument. The member 6 may be merely a frame, or the frame may also serve the purposes of a case, as here illustrated, or there may be provided a separate case as shown in Fig. 8. In Fig. 1, the member 6 may be of any desired size or shape or material. As illustrated, however, it is cylindrical in shape, and made of heavy metal in order that its inertia may be sufficient to put the maximum vibration on the stylus. 7 is a lever arm which turns a few degrees about the knife edge bearing 8, carrying on its upper end a slot or groove, or series of grooves 9, in which the phonograph stylus rests, and having integral with it an armature, 10, made of suitable metal, which is vibrated by a coil, 11. The coil, 11, may be operated by any of the methods common to coils in telephones or loudspeakers, such as a straight electro-magnetic action or the combined permanent-magnetic and electro-magnetic action. To this coil 11 are connected two electric leads (not shown) such as are common to such devices. Opposed springs, 12 and 13, are provided for

keeping the armature at a suitable distance from the magnet. Naturally where a permanent magnet is used, the difference in tension on the two springs will vary as the strength of such permanent magnet—that is, where 11 exercised a constant pull on the armature 10, the tension or pull of the spring 12 will be greater than that of the spring 13. Dead stops are provided, one on the coil itself to prevent "freezing" and one at the other limit position as at 14. The knife-edge supports, or bearings 8 may be supported by means shown in Figs. 2 and 3, but naturally any other type of suitable supports or bearings for the lever 7 may be provided.

Also, it is obvious that any suitable type of opposing springs such as 12 and 13 may be used. 12 and 13 are shown drawn into adjustable tension by the screws 15 which turn in plain holes in the housing 6, and are provided on their inner ends with threaded nuts of suitable type. It may be preferable to pass the screws, 15, through

suitable slots or other openings in the springs and the nuts may have lugs projecting into such slots to prevent turning. Or, naturally, the nuts may be provided with lugs which 5 catch on the outer edges of the springs thus preventing turning. A very nice degree of adjustment may be obtained in use by the mere change in the length and stiffness of the stylus used.

10 Fig. 2 is the same construction shown in Fig. 1, turned 90° about the vertical axis. It will be noted that the flat springs 12 and 13 may be cut on the end diagonally and the points inserted in holes or indentations in 15 any suitable place in 10, or in wings which may be punched from 7. 8 is a triangular piece of glass-hard steel forced into the lever-arm and held by friction. Naturally the lever-arm may have any other suitable construction 20 and any other suitable means of support consistent with the functions which this lever-arm performs. 16 is a piece of suitable metal with suitable V-bearing cut into it, as shown in Fig. 3, and is shown held 25 in 6 by friction.

Fig. 4 shows the construction of Figs. 1 and 2 except that the magnet 11 and the stylus groove 9 are on the same side of the bearing 8.

30 Fig. 5 shows my device designed especially for use with hill-and-dale type of phonograph reproducers. The lever arm in this case is again shown straight with the armature 10 and the needle groove 9 on the same 35 side of the bearing 8, as in Fig. 4. Where the weight of the reproducer (or portion thereof) is a function of the tension on the diaphragm, as is common to hill-and-dale reproducers, it is obvious that one-way spring action is 40 all that is required in my device, and to make same suitable with the several types of such reproducers in use, with widely varying weights, it will be necessary to provide weight resisting spring action adjustable to 45 a reasonably wide range. I have therefore provided a spring, 17 (shown complete in Fig. 6) attached to a spindle or shaft to which is attached a worm wheel, 18, turned by a worm, 19, attached to a thumb-nut, 20. 50 Any other type of spring, and any other type of adjustment may be substituted therefor.

In Fig. 7 I have shown two types of right-angled lever arms, the upper one for lateral and the lower for hill-and-dale use. Obviously a single instrument may be so constructed that by turning the entire instrument 90°, in other words providing it with two bases making approximately right angles with each other, both types of phonograph reproducers may be operated. The levers shown in Fig. 7 may have the included angle as much more or less than a right angle as desired.

60 In Fig. 8 I have shown essentially the same construction as in Fig. 4 with the following

simplifications. The frame, 6, for manufacturing reasons, is used as a support only while the covering is cared for by a housing member, 21. The springs also are simplified, 12 and 13 pressing downward on opposite sides of the bearing 8 and provided with simple tension adjustment screws, 15. The springs in Figs. 1, 2, 4 and 8 are shown as interchangeable but they may not be if other construction is preferable.

75 In Fig. 9 I have shown a modification of my invention in which the radio or electrically operated elements are attached to or are integrally constructed with the phonograph reproducer. (Heretofore in this specification similar numbers have designated similar parts; for Fig. 9 I prefer to use a new number-series beginning at 100.) 100 is a phonograph reproducer provided with a diaphragm, 101. At 102 is attached the usual 80 means of diaphragm actuation. It is shown at 102 turning directly away from the observer, toward the stylus which communicates its vibration to 102 through either lateral or hill-and-dale rig. 103 is an armature 85 vibrated by an electro-magnet, 104. This operation may be, as is common to telephone or loud-speaker practice, using pure electro-magnet or permanent-magnet-electro-magnet combination. 105 is any suitable spring 90 (shown as a flat spring) which may be used for putting one-way tension on the diaphragm, 101. In Fig. 9 it is shown in contact (when in use) with the vibratory member, 102, connected to the diaphragm, 101. 95 To 105 is attached the armature, 103, electrically operated in the manner heretofore described by the magnet, 104. Tension on the spring, 105, is varied by the adjusting nut and screw, 107, by means of the threaded 100 part, 108, so constructed that it may slide lengthwise of 107 but cannot rotate. The spring, 109 holds 108 against the lever, 110, the object of which is to change from phonograph to electric operation and vice versa 105 without changing the adjustment on the spring 105. When the lever 110 is thrown, as indicated, to the left for phonograph reproduction, the threaded part, 108, slides to the right compressing the spring, 109, which 110 allows the spring, 105, or other suitable means 115 of contact, to come out of engagement with the vibratory part, 102, leaving the phonograph operation entirely independent of the electrical. Any other type of "distance" device 120 may be substituted for the lever, 110, which will serve the functions described, or 110 may be located in any suitable position. Naturally this general construction may be 125 built for electric operation only wherein the distance device may be eliminated if desired. I have shown the electrical unit, attached to any phonograph reproducer by any suitable means of attachment as by clamps, 130 111. Naturally electrical elements and pho-

phonograph reproducer may be integrally constructed if desired.

(In Figs. 10 to 13 inclusive I prefer to use a new number series beginning with 200.)

5 In Figs. 10, 11 and 12, 200 is the phonograph reproducer and 201 an armature made in such form that it may be attached to the reproducer preferably as the stylus is now attached. In the drawing it is shown as a

10 piece of magnet metal brazed to a stem 202 preferably of hard copper, hard brass, phosphor bronze, or other suitable non-magnetic metal. This armature may be attached to the reproducer or removed from the same like

15 a phonograph needle. Electro-magnet is shown at 203, the function of which is the same as 11 in Figs. 1 to 8, or 104 in Fig. 9. The magnet 203 is mounted on a frame 204, which is slidably moved to adjusted position

20 by any suitable means such as a thumb nut preferably fixed in such position by suitable means such as a screw, or thumb-nut 206.

The reproducer is supported and held in correct position by any suitable means from the same base 207 as also holds the magnet assembly. Such suitable means may be an adjustable member 208 held by a screw or screws

25 209. To 209 may be adjustably attached brackets or jaws 210 in which the reproducer rests. To 208 or elsewhere may be attached

30 a spring or clip, or other suitable device 211. The object of the adjustments on the supporting members 208 and 210, and the spring 211 is naturally to produce a device that can

readily be adjusted to fit the several makes of 35 phonograph reproducers on the market.

Where this device is made for a single make or type of reproducer naturally these adjustments may be eliminated. The base member 207 may be mounted on another base member 40 212 if desired, preferably used for its weight such as lead. The magnet 203 is shown protected by a guard 213 which slides with it.

In Fig. 13 I have shown a jaw-clip 214 which may be used in place of 210, thus dispensing with the spring 211. Jaw-clips like that shown in Fig. 13 may be made to fit all makes of phonograph reproducers.

The instrument shown in Figs. 10 to 13 may be set, while in use on the phonograph 50 turn-table. The instruments shown in Figs. 1 to 8 may be used the same way, preferably by mounting them on a heavy base as 212 in Fig. 10.

I claim:

A sound reproducing instrument comprising a base adapted to rest on the frame of a phonograph or the turn table thereof, adjustable means carried thereby for supporting the reproducer of such phonograph, an electro-magnetic device including two pole pieces and a coil, an armature comprising a plate and a stem rigid therewith adapted to be clamped in place of the usual stylus by the stylus clamping means of the reproducer, and means for adjusting the distance between said pole pieces and the plate.

WARD LEATHERS.
